UNITED STATES PATENT OFFICE.

ALFRED S. OLIVER, OF MEDICAL LAKE, WASHINGTON.

REFRIGERATOR.

1,370,907.

Specification of Letters Patent.

Patented Mar. 8, 1921.

Application filed November 13, 1918. Serial No. 262,329.

To all whom it may concern:

Be it known that I, ALFRED S. OLIVER, a citizen of the United States, residing at Medical Lake, in the county of Spokane and 5 State of Washington, have invented certain new and useful Improvements in Refrigerators, of which the following is a specification.

The present invention relates to an improved 10 refrigerator of the ice cooled type having end ice boxes and intermediate food compartment. The refrigerator is specially constructed and adapted for use in connection with vehicles and is designed for attachment 15 to the footboard at the side of an automobile or other vehicle. The invention contemplates the utilization of the movement of the automobile while under way, to create a circulation of air through the food 20 compartment and to attain this circulation of the air by the agitation caused to the water from the melted ice in the ice box or tank.

The novelty of the invention resides in the 25 novel combination and arrangement of parts of the refrigerator whereby the device is caused to perform the functions of an efficient refrigerator of this character as will be pointed out in the specification and 30 claims appended.

In the accompanying drawings one complete example of the physical embodiment 35 of the invention is illustrated, as actually used on an automobile, and this exemplification shows the invention constructed according to the best mode so far devised for the practical application of the principles 40 of the invention.

Figure 1 is a longitudinal sectional view 45 through the casing of the refrigerator and the food compartment.

Fig. 2 is a transverse sectional view of the 50 refrigerator upon the line 2-2 of Fig. 1, showing it attached to the foot board at the side of an automobile.

Fig. 3 is a detail perspective view of one 55 of the air valves to the food compartment, which valve is actuated through a float due to the movement of the water level in the ice box.

In the preferred embodiment of the invention as illustrated in the drawings, the 60 casing or chest 1 is constructed of wood or other suitable material, and preferably is 65 rectangular in shape and of the proper di-

mensions, being provided with a lid or cover 2 and locking devices therefor indicated at 3, while at the ends the handles H are provided for convenience in carrying.

As exemplified in the drawings the refrigerator is attached to the foot board 4 at the side of an automobile, the dust guard 5 for one of the wheels being illustrated to give an understanding of the position of the refrigerator, but it will be understood 60 of course that the refrigerator may be carried at any other suitable place on the automobile.

The refrigerator is firmly attached to the foot board of the automobile or car by means 65 of the metallic fastening clips or clamps 6 carried by the chest 1, and the set screws or clamp screws 7 are utilized to hold the refrigerator in place, the screws engaging up against the underside of the foot board as 70 shown best in Fig. 2.

The casing or chest is lined as at 8 with an insulating material, and its inner metallic wall 7' is of course water tight and air tight, and within the casing is positioned a food 75 compartment or metallic tank A spaced from the ends of the casing sufficiently to form the end ice boxes 9 and 10 respectively, and elevated from the bottom of the casing 80 sufficiently to form a communicating passage 85 11 between the two end ice chambers 9 and 10.

Laterally, the tank A forming the food compartment, the side walls of the tank being formed by the wall 7' of the casing, extends 90 to the walls of the casing and is attached to the walls as a support, and the entire upper, open end or top of the food compartment is closed by an air tight cover 12 securely fastened down by means of the nuts 95 13 and screws 13', and similar covers 9' and 10' are provided for the ice chambers at the ends of the casing.

In the upper end walls of the compartment A are provided port holes 14 establishing communication between the interior of the compartment and the two end ice chambers. A suitable number of these port holes are provided in the end walls and each port hole is provided with a pivoted valve or 100 closure 15 in the form of a flat disk secured on the pivot or hinge bar 16 that is rotatable in the cleats 17 by means of which the valve is supported at the outside face of the compartment ends. A lever arm 18 is ex- 105 110

tended at right angles to the pivot bar 16 and the buoyant float 19 on the end of the arm moves in close proximity to the side walls of the chest in the ice chambers.

5 The construction and operation of the device thus described and illustrated are so simplified that the action of the parts will readily be understood by one skilled in the art. With the cakes of ice in their respective chambers, and before any water accumulates in the bottom of the casing, the port holes are held open by the floats 19 which act as weights, and the circulation of air is provided for through the food compartment.

10 After the ice cakes have melted somewhat and water accumulates in the bottom of the casing, the water is caused to move from end to end of the refrigerator as the automobile changes position due to differences in grade. Thus, if the automobile is moving to the right in Fig. 1 and is going down-grade, the right end of the casing will be lower than the left end and consequently 20 the water will flow to the right end driving the air ahead of it and causing the air to pass through the port hole at the right end of the compartment A and out through the left end port hole, the water thus displacing the air as the former flows back and forth. The valves 15 of course remain open unless the water level rises high enough to 30 lift the float 19 and in which case, the rising of the float will close the port hole, 35 thus preventing ingress of water to the food compartment.

When the refrigerator is detached from the automobile it may stand upon the clamp

screws 7 and special lugs 20 on the fastening clips 6, as supports.

40 What is claimed herein:—

1. A portable refrigerator comprising a closed casing having an intermediate water tight food compartment therein spaced from the ends and elevated from the bottom of the casing to form end ice chambers and a bottom passageway to permit movement of water, and said compartment having cold air port holes in its end walls and gravity actuated closures for said port holes as described.

45 2. A portable refrigerator comprising a closed casing with a receptacle therein forming a closed water tight compartment for food, said receptacle filling the casing in one direction and spaced from the ends of the casing to form ice chambers in the other direction and also elevated from the bottom of the casing to provide a passageway between said chambers for movement of 50 water to create circulation of air, and said compartments having openings into the ice chambers with gravity operated means for closing said openings when the casing is 55 tilted.

60 3. The combination with a portable casing and a water tight food compartment therein having air ports communicating with the casing, and oppositely opening gravity operated valves for permitting air circulation through said ports, whereby the movement of water due to tilting of the casing causes circulation of air, as described.

65 In testimony whereof I affix my signature.

70 ALFRED S. OLIVER.
